UNITED STATES PATENT OFFICE.

CHARLES E. LIPE AND JOHN LIGHTON, OF SYRACUSE, NEW YORK.

COIN-CONTROLLED TEST LIFTING AND PULLING MACHINE.

SPECIFICATION forming part of Letters Patent No. 425,892, dated April 15, 1890.

Application filed May 23, 1889. Serial No. 311,855. (No model.)

To all whom it may concern:

Be it known that we, CHARLES E. LIPE and JOHN LIGHTON, of Syracuse, in the county of Onondaga, in the State of New York, have 5 invented new and useful Improvements in Coin-Controlled Test Lifting and Pulling Machines, of which the following, taken in connection with the accompanying drawings, is a full, clear, and exact description.

10 Our invention relates to improvements in coin-controlled test lifting and pulling machines of the particular class which are designed to be placed in public places, and are adapted to be operated only upon the insertion of a proper coin, and which are normally locked against operation when no coin is inserted.

15 This invention is particularly an improvement on the device set forth in the patent, 20 No. 397,229, issued to John Lighton as the assignee of Bernard Fuchter, and the device set forth in the application, Serial No. 323,231, of John Lighton, and has for its object the production of a simple, effective, and cheaply-25 manufactured construction of machine, which can be operated when the proper coin is inserted and is normally locked against operation when no coin is inserted; and to this end our invention consists, essentially, in a tensioned lift-bar and a locking-dog adapted to engage and lock the lift-bar from operation when no coin is inserted, said dog being prevented from operation when the coin is inserted into the machine.

30 This invention furthermore consists in combining with the aforesaid lifting-bar and coin-controlled locking-dog a construction of knife for cutting off strings, wire, and like articles attached to a coin for the purpose of 35 repeatedly operating our machine with the same coin; and it furthermore consists in hinging the portion of the frame or case of our machine containing the lift-bar and coin-controlled mechanism to a stationary base, 40 whereby the angle of the lifting-bar may be varied to suit the position of the operator, and in a lock for locking the said hinged portion of the frame to the stationary base.

45 The invention also consists in the detail 50 construction and arrangement of the parts, all as hereinafter more particularly described, and pointed out in the claims.

In describing our invention reference is had to the accompanying drawings, forming a part of this specification, in which like letters indicate corresponding parts in all the views.

55 Figure 1 is a front elevation of our improved machine. Fig. 2 is a front elevation of the upper part of our machine, with the dial and face removed. Fig. 3 is a rear elevation, the back or outside case being removed, of the parts illustrated in Fig. 2. Fig. 4 is a longitudinal section of the upper part 60 of our machine, taken on line 4 4, Fig. 2. Fig. 5 is a cross-sectional view taken on line 5 5, Fig. 2. Fig. 6 is a sectional view, taken on line 6 6, Fig. 4, of the detached upper part 65 of the parts of our machine illustrated in Figs. 3 and 4. Fig. 7 is a horizontal sectional view 70 taken on line 7 7, Fig. 6. Fig. 8 is a sectional view taken on the opposite side of said section-line 7 7, Fig. 6. Fig. 9 is a cross-section taken on line 9 9, Fig. 4, illustrating particularly the construction of the knife for clipping off a 75 cord or wire attached to the operating-coin. Fig. 10 is a detached view of the locking-dog. Fig. 11 is an inverted plan of the collar secured to the lift-bar to form a support for the spring tensioning the said bar. Fig. 12 is a 80 sectional view taken on line 12 12, Fig. 11, still further illustrating said supporting-collar for the spring. Fig. 13 is a detached sectional view taken on line 13 13, Fig. 1, illustrating the construction of the lock for locking the hinged case containing the working 85 parts of the machine to its supporting-base. Figs. 14 and 15 are sectional views taken, respectively, on lines 14 14, Fig. 13, and 15 15, Fig. 14, further illustrating the locking device therefor; and Fig. 16 is a sectional view 90 illustrating a modified form of the locking device to that illustrated in Figs. 13, 14, and 15.

95 The main frame A of our improved machine is preferably of circular form, braced by vertical tie bars A' and cross-bars A'', and covered by a suitable casing A³, which may be made highly ornamental. The frame A is supported upon a suitable hollow standard B 100 containing the money-box, which is not illustrated, and is of any desirable form and construction to receive and contain the coins dropped through the machine for operating

the same. The hollow standard B is supported by the base B', and is preferably hinged thereto, as will be hereinafter described.

5 Supported in the frame A, and preferably guided vertically therein by the guideway A⁴, is the lift-bar C. The lower extremity of this bar C abuts against a seat A⁵ of the frame A, and the upper extremity is provided with the handle D, preferably adjustable thereto. A collar E, (illustrated in Figs. 11 and 12,) is secured to the lift-bar, preferably above the guide-bearing A⁴. A spring F is interposed between this collar E and a collar or seat G, bearing against a seat A⁶ in the upper part of the frame A. These collars E and G are preferably formed with the flanges or shoulders e and g, and the extending hubs e' and g'. The lower and upper coil of the spring F encircles the said hubs e' and g' and abuts against the said shoulders e and g. It will thus be seen that when the handle is released the spring F, abutting against the collar E, retracts the lift-bar and forces its base against 25 the seat A⁵.

By reference to Fig. 5 it will be seen that the lower part of the lift-bar is angular in cross-section.

In order to place the collar E upon the lift-bar, the said collar is formed with the opening E', of like form to the cross-section of the lower part of said lift-bar. The lower face of the collar E is formed with the cut-outs E², which form shoulders E³. The upper part of 35 the lift-bar is cylindrical in form, to allow the handle D to adjust thereupon, and accordingly, after the lift-bar has been slipped through the collar so that the same is above the angular part of said bar, the collar is 40 slightly twisted or rotated, so that the shoulders E³ are abutted by the angular corners of the lower part of the lift-bar, firmly securing the collar to said bar by the pressure of the spring bearing upon said collar.

45 Pivoted to the frame A at any suitable point h is the locking-dog H, which is forced toward the lift-bar C by means of a spring I, attached to the dog H in any desirable manner.

50 Secured to the frame A, and preferably arranged vertically therewith, is the coin-chute J, which may be made of any desirable form or construction, and is illustrated as formed of a piece of straight metal bent around in 55 the desired shape. The lower part of the coin-chute is formed of a plate J', preferably constructed of steel or other hard metal, and secured by screws j to the frame.

Provided in the coin-chute J, or rather in 60 the plate J', is the cut-out J², which opens into the passage j' of said coin-chute. The dog H is formed with a shoulder H', which is constantly forced into the cut-out J² in such a manner that the said shoulder inclines from 65 the top downward toward the center of said passage j'. The shoulder H' of the dog H projects within the coin-chute sufficiently far so

that when a nickel is dropped from the entrance-opening of said chute down through the slot or passage j' of the chute it will 70 be checked from further movement when it reaches said shoulder.

The lift-bar C is provided with a notch C', formed with inclines c and c', leading respectively upwardly and downwardly therefrom. 75

Provided upon the dog H is a projection H², which is preferably cut away at h³, and normally bears against the incline c of the lift-bar. A slight space intervenes between the lower edge or impinging shoulder H⁴ of 80 the dog H and the shoulder C² of the notch C' of the lift-bar C.

When, by reason of force applied to the handle D, the lift-bar is elevated, it will be evident that the spring I will force the dog 85 toward the said lift-bar, and that as the incline c is raised the shoulder H⁴ of the dog H will engage the shoulder C² of the notch C', and prevent the further movement of the lift-bar. However, if a nickel or other proper 90 coin is first dropped through and is caught between the face H' of the dog H and the adjacent face of the coin-passage j' it will be seen that the spring I is unable to approximate the dog H toward the lift-bar, and consequently when the lift-bar C is raised the 95 said locking-dog is prevented or blocked from action, as the shoulder H⁴ of the said dog H will not be contacted with the shoulder C² of the notch C', and therefore the lift-bar can 100 be readily raised. As the lift-bar is raised, it will be evident that the incline c', leading downwardly from the slot C', will force backward the dog H, and will allow the nickel to pass through the chute into the money-box, 105 which, as described, is preferably supported in the hollow standard B.

Secured to the lift-bar C is a rack R, arranged at one side of the diametric center of the machine, and formed with teeth on the 110 face adjacent to the said center.

Supported in the tie-piece A⁷, secured to the bars A', is a spindle S, having its inner end formed with teeth s, engaging the rack R. The outer extremity of the spindle S is 115 preferably formed with a shoulder S' on the outside of the dial U, which shoulder retains the dial in its position. Formed or provided upon the outer extremity of the said spindle S is a lug s', which engages the 120 indicator-finger U' and forces the same around the dial to indicate the amount pulled when the lift-bar is elevated. The indicator-finger U' is preferably supported by the glass face V of our machine, and is secured thereto 125 in any desirable manner which will allow the same to readily turn around said face. On the outside of the face V is a thumb-nut v, by means of which the indicator-finger is turned back to its normal position. 130

Depending from the handle D is the hub D', of suitable length to give the desired adjustment of said handle. The lower part of said hub is formed with threads d, which en-

gage the threads provided upon the upper part of the lift-bar. Above the threads d , and preferably extending to the top of the handle D, is the chamber d' , of greater diameter than the diameter of the roots of the threads d . It will thus be seen that above the threads d is formed the shoulder d^2 . Secured at the top of the lift-bar, and preferably provided with a thread reversely turned to that of the lift-bar, is the screw 1. The head 2 of said screw is preferably of a diameter sufficiently less than the diameter of the chamber d' to allow the said chamber to readily pass up or down as the handle is adjusted. The hub D' of the handle is guided in the guide-hub K, preferably secured on the outside of the frame A, and formed with the upper face or shoulder K'. Secured in the top of the chamber d' by a pin d^3 is the filling-piece D², which is preferably provided with a handle D³ to allow of a pull of the lift-bar with only one hand. When the handle is adjusted upward, the shoulder d^2 of the chamber d' will abut against the under face of the head 2 of the screw 1, thus preventing the withdrawal of the handle. When the handle is adjusted downward, the lower face of the filling-piece D² will abut against the top face of said screw-head 2, and will thus limit the downward movement of the handle. The hub of the handle D is preferably formed with the annular shoulder D⁴ above the casing A³ of our machine. The abutment of the lower face of the filling-piece with the top face of the screw-head 2 is preferably so timed as to occur just before the shoulder D⁴ of the handle-hub abuts against the top face or shoulder K' of the guide-hub K. It will be understood that if the shoulder D⁴ were allowed to abut against the shoulder K' the handle, although prevented from downward movement, could still be turned around, and would draw up the lift-bar against the action of the spring-dog, thus unduly straining the parts.

Hinged to the frame A in any suitable manner and just above the plate J' is the knife L, provided with the cutting-edge L', working in a slot j^3 , provided in said coin-chute. Connected to said oscillating knife L by a tie-bar l is the oscillating plate M, preferably on the opposite side of the central portion of the frame interposed between the lower parts of the vertical tie-bars A'. When the lift-bar is elevated, a shoulder C³ provided thereupon forces outward the plate or bar M. The said plate, by the tie-rod l, then forces inward the knife L, and causes the same to shear across the top face of the plate J', which, as described, is preferably formed of steel. A suitable spring J³ is attached to the knife L, and after the operation of the knife said spring retracts the same to its normal position. It will thus be seen that should a cord or wire be secured to the nickel or other proper coin the knife L will shear the same off, and that the operator will be unable to withdraw the coin from the chute.

It will be understood that when operating our improved machine, as described, the back of the operator is bent and that a great strain 70 comes thereupon. In order to adapt the machine to persons who are unwilling to subject their back to the said strain, we prefer to form the same so that the frame containing the working parts of the machine can be tilted 75 at an angle to the base B'. When the said frame is tilted, as described, the operator may sit upon a chair or a sliding seat, (not necessary to here illustrate or describe,) and by reason of the tilting of the frame A the 80 bending of his back is obviated, and the strain thereupon is greatly reduced.

In order that the frame containing the working parts of our machine may be tilted at an angle with the supporting-base, we form 85 upon the hollow standard B the base B², which, by means of a suitable shaft or stud b, is hinged to lugs b', projecting upwardly from the supporting-base B'. This base B² of the supporting-standard B of our machine is normally locked to the supporting-base B', and preferably by a lock which locks the said parts automatically.

By reference to the drawings it will be seen that the illustrated form of the base B² is 95 semicircular, and that on the interior thereof we provide the notches or teeth b³, preferably arranged on each side of the center of said base. Projecting from beneath said base B², through slots b⁴ provided therein, are the 100 levers or rods o, sliding in suitable guideways o', provided on the supporting-base B'. These rods lie in a right line and are connected together by the toggle-levers o².

Hinged at o³ to the adjacent extremities of 105 the toggle-lever is a rod or bar N, sliding in guideways n, provided on the supporting-base B'. The extremity of this bar N is guided by an opening B⁴ provided therein. The outer extremity of this opening is preferably enlarged and is filled by the nipple B⁵, through which slides the forward extremity of the rod N. Provided upon said rod is the shoulder N', between which shoulder and the inner face of the enlargement of the opening B⁴ is 115 interposed the spring N², which constantly forces outward the rod N, straightens the toggle o², and engages the locking-rods o with the notches b², thus automatically locking the frame of our machine to the supporting-base B'. 120

When it is desired to change the altitude of the frame of our machine, the forward outward extremity of the rod N is forced inward, preferably by the operator's foot, and the 125 locking-levers o are then, by means of the toggle o², withdrawn from engagement with the notches or teeth b³. The supporting-frame can then be readily tilted to the desired angle with the base, and upon releasing 130 the foot the pressure of the spring N² automatically locks said parts.

At Fig. 16 we have shown a modified form of the locking device, in which a serrated or

notched disk or gear W is secured to the said pivotal pin b. Projecting through an opening S, formed in the base B², is a stud T, the lower extremity of which engages the notches or teeth of the serrated disk or gear. The upper part of the opening S is closed by a nipple T'. A shoulder t is provided upon the stud T, and interposed between said shoulder and the inner face of the cut-out S is a spring S', which normally forces said stud T upward. It will thus be seen that, when in its normal position, the frame containing the working parts of our machine is free to be turned in any position in relation to the supporting-base B. The outer extremity of this stud T is so arranged that when the operator places his feet upon the machine in position for operating the same he depresses the said stud and causes its lower extremity to engage said serrated disk, thus automatically locking the frame containing the working parts to the supporting-base during the operation of the machine.

It will be understood that there may be other mechanisms to lock the hinged standard B to the supporting-base B', and that such means may operate either automatically or not, as desired.

The operation of our invention will be readily perceived from the foregoing, and it will be understood that considerable change may be made in the detail construction and arrangement of the parts of our invention without departing from the spirit thereof.

Having thus fully described our invention, what we claim as new, and desire to secure by Letters Patent, is—

1. In a test lifting and pulling machine, the combination of the lift-bar, a notch provided on said bar, inclines leading, respectively, from the top and the bottom of said notch, and a locking-dog for engaging the notch of the lift-bar, said dog being blocked from action by the insertion of a proper coin, substantially as and for the purpose described.

2. In a test lifting and pulling machine, the combination of a lifting-bar, a notch in said lifting-bar, an incline leading from said notch, a locking-dog for engaging said notch and incline, a coin-chute having a cut-out or opening, and a face provided on said locking-dog and adapted to enter said cut-out in the coin-chute and prevent said dog from locking the lift-bar when a coin is fed down said chute, substantially as described.

3. In a test lifting and pulling machine, the combination of a lifting-bar, a notch in said lift-bar, an incline leading from said notch, a locking-dog for engaging said notch and incline, a coin-chute having a cut-out or opening, a face provided on said locking-dog and adapted to enter said cut-out in the coin-

chute and prevent the said dog from locking the lift-bar when a coin is fed down said chute, a handle adjustably mounted on said lift-bar, whereby the same is operated, and a stop device for checking the downward movement of the handle and preventing straining of the aforesaid locking-dog, substantially as specified.

4. In a test lifting and pulling machine, the combination of a lift-bar having one portion thereof angular in cross-section, a spring encircling one extremity of said bar for forcing the same to its normal position, a collar E, having the angular cut-out E² and shoulders E³, and a locking-dog for engaging the lift-bar, said locking-dog being prevented from action when a proper coin is inserted, substantially as and for the purpose set forth.

5. In a test lifting and pulling machine, the combination of a lift-bar and means, substantially as described, for locking said bar when no coin is inserted, a knife for cutting off strings or wires inserted into the machine, an oscillating plate connected to said knife, and a shoulder provided upon said lift-bar for engaging said plate and operating the knife after the commencement of the motion of the lift-bar, substantially as and for the purpose set forth.

6. In a test lifting and pulling machine, the combination of a lift-bar and means for locking said bar when no coin is inserted and allowing the operation of said bar upon the insertion of a proper coin, with the coin-chute J, the plate J', the knife or plate L, shearing across said plate J', a shoulder provided upon the lift-bar, and a connection to the plate L, for operating the same to shear across the plate J' upon the operation of the lift-bar, substantially as and for the purpose specified.

7. The combination of a lift-bar, a handle for operating said lift-bar, means, substantially as described, for locking said lift-bar when no coin is present, a supporting-standard for said parts and a supporting-base for said standard hinged thereto, whereby the said standard may be tilted at any desired angle and the lift-bar operated when the operator is seated, and a lock for locking said standard to said supporting-base, substantially as described.

In testimony whereof we have hereunto signed our names, in the presence of two attesting witnesses, at Syracuse, in the county of Onondaga, in the State of New York, this 9th day of May, 1889.

CHARLES E. LIPE.
JOHN LIGHTON.
